CLAIM

The ornamental design for a bicycle shoe, as shown and described.

DESCRIPTION

FIG. 1 is a perspective view of a bicycle shoe in accordance with a first embodiment of my new design;

FIG. 2 is a first side elevational view thereof;

FIG. 3 is a second side elevational view thereof;

FIG. 4 is a top plan view thereof;

FIG. 5 is a bottom plan view thereof;

FIG. 6 is a first (toe) end elevational view thereof;

FIG. 7 is a second (heel) end elevational view thereof; and,

FIG. 8 is a bottom plan view, similar to FIG. 5, of a bicycle shoe in accordance with a second embodiment of my new design, which is identical to the bicycle shoe illustrated in FIGS. 1 to 7, except that a boundary of the bicycle shoe is shown in broken lines.

A third embodiment of my new design is identical to the first embodiment, except that the third embodiment includes the mirror image of the bicycle shoe shown in FIGS. 1 to 7.

A fourth embodiment of my new design is identical to the second embodiment, except that the fourth embodiment includes the mirror image of the bicycle shoe shown in FIG. 8.

The broken line portion of the bicycle shoe is for the purpose of illustrating the remaining structure of the bicycle shoe and forms no part of the claimed design.

The dot-dash broken line defines the bounds of the claimed design and forms no part thereof.
